UNITED STATES PATENT OFFICE

154,506

DESIGN FOR AN OUTDOOR SWITCH BOX

Charles Opalek, Brooklyn, N. Y.

Application September 15, 1948, Serial No. 148,595

Term of patent 14 years

(Cl. D26—5)

To all whom it may concern:

Be it known that I, Charles Opalek, a citizen of the United States of America, and a resident of Brooklyn, in the county of Kings and State of New York, have invented a new, original, and ornamental Design for an Outdoor Switch Box, of which the following is a specification, reference being had to the accompanying drawings, forming part thereof.

Fig. 1 is a front elevational view of an outdoor switch box, showing my new design.

Fig. 2 is a side elevational view of the same.

Fig. 3 is a bottom plan view of the same.

Fig. 4 is a rear elevational view of the same.

The dotted line showing of a portion of a sup-

port in Figs. 1, 2 and 3 is for illustrative purposes only.

I claim:

The ornamental design for an outdoor switch box, as shown and described.

CHARLES OPALEK.
